HIS ATTORNEY.

UNITED STATES PATENT OFFICE.

ERNEST D. CHARTERS, OF SANTA CRUZ, CALIFORNIA, ASSIGNOR TO CHARTERS MANUFACTURING CO., OF SANTA CRUZ, CALIFORNIA.

TEMPERATURE-REGULATING DEVICE FOR INCUBATORS AND BROODERS.

1,386,990.

Specification of Letters Patent.

Patented Aug. 9, 1921.

Application filed January 27, 1919, Serial No. 273,304. Renewed August 24, 1920. Serial No. 405,735.

To all whom it may concern:

Be it known that I, ERNEST D. CHARTERS, a citizen of the United States, residing at Santa Cruz, in the county of Santa Cruz 5 and State of California, have invented a new and useful Improvement in Temperature-Regulating Devices for Incubators and Brooders, of which the following is a specification.

10 My invention relates to improvements in temperature regulating devices for incubators and brooders in which the temperature within and outside the incubator or brooder to which it is attached, work together in regulating the heat applied to their inner chambers or compartments and its objects are:

First, to provide a temperature regulating device for incubators and brooders that 20 will automatically control the temperature within the incubator or brooder when sudden changes in temperature occur in the weather or atmosphere outside of or surrounding the incubator or brooder.

25 Second, to provide a temperature regulating device for incubators and brooders that will save fuel by regulating the size of the flame derived from a wick burner.

Third, to provide a temperature regulating device for incubators and brooders that 30 is very compact, and is inexpensive to construct.

Fourth, to provide a temperature regulating device for incubators and brooders and 35 the like that may be used to actuate a damper or other draft regulators.

With these and other objects in view my 40 invention resides in certain novel features of construction and in the unique arrangement of parts to be hereinafter more fully described and claimed, it being understood that various changes in form, proportion and minor details of construction may be resorted to within the scope of the appended 45 claims.

For a full understanding of the invention and the merits thereof, reference is to be had to the following description and to the accompanying drawings forming a part of this 50 specification in which similar reference characters represent corresponding parts in all the views.

55 Figure 1 is a front view of an incubator showing my regulating device attached thereto, parts broken away.

Fig. 2 is an enlarged front view of the regulating device, parts assembled.

Fig. 3 is a sectional view as shown on line 3-3 of Fig. 2.

Fig. 4 is a side view of a wick oil-burner, 60 showing the flame controlling mechanism, part broken away.

Fig. 5 is a perspective view of the flame and wick, showing means for controlling the size of flame.

65 My improved temperature regulating device for incubators and brooders, forming the subject matter of the present invention consists of a U-shaped bracket 1 having one leg longer than the other. Fastened to the 70 longer leg and at right angles thereto is a length of tubing 2 screw threaded or otherwise suitably fastened in place, on the shorter leg of the bracket 1 is a U shaped saddle 3, 75 adjustably fastened in place and having notches 4 in the upper edges adapted to receive the trunnions 5 of the counterbalanced actuating lever 6, the counterweight being shown at 6^a.

80 A distance from the trunnion end of the actuating lever 6 is shown the adjusting screw 7 screw threaded through the lever 6 at right angles to the trunnions and being held in adjusted position by friction spring 7^a.

85 To the upper end of the adjusting screw 7 is fastened a multiple hollow-disk thermostat 8 containing volatile liquid, said thermostat being adjusted to operate most efficiently at between the temperatures of 90 30° and 100° Fahrenheit. The tubing 2 passes through the floor 9 of an incubator or brooder 9^a into the inner compartment 10 and is secured in place by means of washer 10^a and clamp 10^b and also by the outside 95 brace 10^c. A spring lock-washer is shown at 11 adapted to resiliently bind the tube 2 in position.

To the upper end of the tube 2 is secured a second thermostat 12, similar to the thermostat 8 but adjusted to operate most efficiently between the temperatures of 90° to 110° Fahrenheit, said thermostat being held in place by a suitable yoke 13.

100 The thermostats 8 and 12 are kept in operative connection with each other by means of the adjusting screw 7 and the rod 14 which passes through the tube 2, the ends of which rest against the center of each thermostat.

105 A wick kerosene oil burner 15, having 110

flame controlling shutters 15^a and actuating cranks 15^b is operatively connected to the actuating lever 6 by a suitable link 16, the burner thus being provided with flame controlling mechanism actuated by the lever 6, permits the flame 17 to be automatically restricted or enlarged as the temperature of the incubator or brooder and the outside temperature affects the thermostats.

10 Adjustment of the screw 7 will also tend to vary the distance between the thermostat 8 and the lever 6 which will change the relative position of the lever 6, consequently effecting the operation of the shutters 15^a in extinguishing the flame 17, as will be readily understood.

A font or tank, to which the burner is attached, is shown at 18, suspended from the floor 9 of the incubator or brooder 9^a in such 20 a manner that the flame controlling shutter cranks 15^b may be operated by the actuating lever 6.

The heat derived from said burner flame may be distributed to the inner compartment 10 of the incubator or brooder 9^a in 25 various ways now being used in such structures, my invention relating more particularly to the automatic regulation of the heat to be distributed.

30 It will be seen from the foregoing description that the inner compartment of an incubator or brooder equipped with my improved temperature regulating device will be automatically protected against any 35 changes in the temperature therein by changes in the air surrounding the incubator or brooder, as well as against changes in the conditions within said compartment, and that, therefore, the attention of an operator is greatly lessened.

The operation of my improved temperature regulating device for incubators and brooders is as follows:—

Any changes in temperature will affect 45 the thermostats 8 and 12, heat causing an expansion of the volatile liquid within the thermostats, bulging them out or making them thicker; cold having the reverse action.

50 The regulating device and flame being adjusted to maintain a certain temperature within the compartment 10, a lowering of the temperature, either inside or outside, will cause the respective thermostat to become thinner, thus allowing the actuating lever 6, by the action of the counterweight 6^a, to raise or swing upward a distance which, in turn, opens the shutters 15^a and allows a larger flame to burn therebetween.

60 A raising of the temperature causes the reverse of this action.

Having thus described my invention, what I claim as new and desire to secure by Letters Patent is:—

65 1. In a device of the character disclosed,

a standard, a pair of brackets on said standard, a lever mounted upon one of said brackets, a thermostat mounted upon said lever, a thermostat mounted upon the other bracket, and a rod extending through said standard and engaging both of said thermostats.

2. In a device of the character described the combination of an incubator, a tube passing through a wall of the incubator, 75 brackets supported upon the ends of the tube, a lever situated outside of the incubator and fulcrumed upon one of said brackets, a rod passing through said tube, an adjustable member carried by said lever and 80 arranged in alinement with said rod, a thermostat within the incubator and supported between one end of said rod and the other of said brackets, and a second thermostat located outside of the incubator and 85 supported between said adjustable member and the opposite end of said rod.

3. In a temperature regulating device of the class described, an incubator; a thermostat positioned outside said incubator; a second thermostat positioned within said incubator; a tube passing through the floor of the incubator to which the second mentioned thermostat is attached; means for attaching the tube in place in the incubator; 90 a U-shaped bracket, one leg of which is attached to the outer end of the tube at right angles thereto; a saddle having notches in the upper edges thereof, said saddle being adjustably attached to the other leg of the 100 bracket; a counterbalanced lever; trunnions on said lever adapted to engage said notches in the saddle; an adjusting screw adapted to be screwed through said lever and in alinement with said tube; means for attaching 105 the first mentioned thermostat to the adjusting screw; a rod adapted to pass through the tube and rest against each thermostat whereby the counterbalanced lever is caused to move through a limited arc by the contraction and expansion of the thermostats.

4. In an incubator temperature regulator, a heating means for the incubator; a pivotally supported controlling lever connected to said heating means for controlling the 115 same, a thermostat mounted on the lever, a second thermostat having a fixed position relative to said first thermostat, one of said thermostats being disposed within and the other outside of the incubator, said thermostats operating at different temperatures, an operative connection extending between said thermostats and with which the latter have abutting engagement, whereby the effective movements of the respective thermostats are 120 transmitted to said lever, a pressure means acting on said lever in opposition to said thermostats, and means for varying the relative distance between said lever and said first 125 thermostat for the purpose set forth.

5. In a device of the character disclosed, a standard, a pair of brackets on said standard, a lever mounted upon one of said brackets, a thermostat mounted upon said lever, a thermostat mounted upon the other bracket, said thermostats being effectively operable at different degrees of temperature to actuate said lever, and an operative connection between said thermostats and with 50 which the latter have abutting engagement whereby the effective movements of the thermostats are transmitted to the lever.
- 10 6. In a device of the character described, the combination of an incubator, a standard passing through a wall of the incubator, brackets supported upon the ends of the standard, a lever situated outside of the incubator and fulcrumed upon one of said brackets, an adjustable member carried by 55 said lever, a thermostat within the incubator maintained in position by the other of said brackets, a second thermostat located outside of the incubator and supported by said adjustable member, and a rigid connection extending through the standard, whereby the effective movements of the thermostats are transmitted to the lever, said adjusting screw 60 varying the relative distance between the said second thermostat and the lever for the purposes set forth.
- 15 7. In a device of the character described, a standard, a thermostat on one end of the standard, a lateral offset bracket on the other end of the standard and extending beyond said end thereof, a controlling lever pivoted on the bracket, a second thermostat mounted on the lever and in substantial axial alinement with said first thermostat, a connection 65 between the thermostats whereby the effective movement of each is transmitted to the lever, and an adjustable member for varying the relative distance between the 70 said second thermostat and the lever for the purpose set forth.
- 20 8. A device of the character described for incubators, comprising a standard to be positioned within an incubator and having a 75 thermostat thereon in longitudinal alinement therewith, a substantially U-shaped bracket extending beyond the standard and having one leg attached to an end of the standard, the legs of the U-shaped bracket extending substantially at right angles to the standard, a counter-balanced lever pivotally supported on the other leg of said bracket, an adjusting screw threaded in said lever, a second thermostat supported by said adjusting screw and positioned in longitudinal alinement with the standard, and a connection between said thermostats extending through the standard, whereby the effective movements of the thermostats are transmitted to the lever, said adjusting screw 80 varying the relative distance between the said second thermostat and the lever for the purposes set forth.
- 25 9. The combination with an incubator having a heating unit, of a bracket secured 85 to an exterior wall of the incubator, a heat-controlling lever having one end thereof connected with said heating unit and having its other end pivotally mounted on said bracket, a thermostat mounted on the lever, 90 a thermostat mounted within the incubator, said thermostats being adapted to operate effectively at different temperatures, a connection between the thermostats, whereby the movements of the thermostats are transmitted to the lever, a screw threaded in the lever and adjustably supporting said first mentioned thermostat, a counterweight extension for the lever having a portion parallel with said adjusting screw extending 95 from an intermediate portion of the lever and another portion extending beyond the pivotal point of the lever, and a clip on the portion of said extension parallel with the screw for engaging the latter and maintaining it in adjusted positions.
- 30 10. In testimony whereof I hereby affix my signature at Santa Cruz, Santa Cruz County, California, this 20 day of Jan., 1919.
